UNITED STATES PATENT OFFICE.

ALBERT T. LOFTSGAARDEN, OF POWELL, WYOMING.

DOOR-CLOSER.

1,244,621.

Specification of Letters Patent.

Patented Oct. 30, 1917.

Application filed March 21, 1916. Serial No. 85,583.

To all whom it may concern:

Be it known that I, ALBERT T. LOFTSGAARDEN, citizen of the United States, residing at Powell, in the county of Park and State 5 of Wyoming, have invented certain new and useful Improvements in Door-Closers, of which the following is a specification.

My present invention has to do with spring-actuated door-closing devices; and 10 it has for its general object to provide a simple and durable device, susceptible of ready application to a door and door frame, without the employment of skilled labor, and one that is reliable in the respect that 15 it has the capacity of promptly and strongly returning a door to and retaining the same in its closed position.

To the attainment of the foregoing and other objects the invention consists in the 20 generic combination and specific embodiments hereinafter described and definitely pointed out in the claims appended.

In the accompanying drawings which are hereby made a part hereof:

25 Figure 1 is a perspective of the preferred form of my invention.

Fig. 2 is a horizontal section through the door and door casing and showing the improved device in plan.

30 Fig. 3 is a transverse section taken on the line 3—3 of Fig. 2 and showing the pivotal connection between the swinging arms of the device.

Referring by numeral to the drawings:

35 1 is the side stile of a door frame, and 2, a door, hinged to the stile in the ordinary or any other suitable manner, as shown in Fig. 1.

In furtherance of my invention the stile 40 1 and door 2 are provided on their faces with brackets 4.

To the stile bracket 4 is hinged one end of the arcuate, horizontally-swinging arm 5. The said arm 5 is provided adjacent to its 45 middle with a loop-shaped outwardly-extending portion 6, and its free end 5^x is arranged comparatively near the outer side or face of the door 2 as best shown in Fig. 2; the said free end being preferably provided 50 with an upstanding apertured lug 7.

The bracket 4 on the face of the door 2 serves for the pivotal connection of a second horizontally-swinging arm 8. This arm 8 is also of general arcuate form, and is ar- 55 ranged with its free end 8^x adjacent to the

face of the door. Near its middle the arm 8 is provided with an outwardly extending loop 9 which straddles the portion 6 of the door arm 5 and is pivotally connected thereto, preferably through the medium of a 60 pintle 10 which enables each arm to swing on the other. It will be apparent that this arrangement disposes the arm portions 8^x and 9^x at the same side of the door closer considered as a whole which is desirable 65 inasmuch as it promotes free working of the spring that will now be described. It will also be apparent that the free end of the arm portion 8^x is shaped as a hook, Fig. 1, this being materially advantageous inasmuch as the spring can be readily unhooked, thereby allowing the door to be left open when desired.

Interposed between the free ends of the swinging arms 5 and 8 and connected therewith is a retractile spring 11 equipped with means 12 for regulating the tension thereof.

In the preferred arrangement, the spring 11 at one end is connected directly to the end 8^x of the arm 8, and the opposite end of the spring is coiled back of a nut 13 which in combination with a bolt 14 forms the tension-regulating means for the spring. The said bolt 14 extends through the aperture of the lug 7 and has a kerfed head back 85 of said lug, and hence it will be understood that turning of the bolt will be attended by tightening or loosening of the spring according to the direction in which the bolt is turned.

Manifestly on opening of the door 2, the free ends of the arms 5 and 8 will be moved away from each other, and the spring will be stretched or put under tension. Consequently when the door is released and the 95 spring contracts to its normal state, the spring will operate through the arms 5 and 8 to close the door, and this promptly and powerfully because of the considerable leverage the spring is enabled to exert.

It will be appreciated from the foregoing that the embodiment thus far specifically described is simple and strong, and is well adapted to withstand shocks and rough usage as well as exposure to the weather. I 100 would also direct attention to the fact that in said embodiment the retractile spring is connected to the portion of one swinging arm that extends beyond the pivotal connection of the arms each to the other.

Having described my invention, what I claim and desire to secure by Letters Patent, is:

1. In a door-closing device, the combination of a door frame, a door hinged thereto, brackets fixed on the faces of the frame and door, an arcuate, horizontally swinging arm pivoted at one end to the frame bracket and having a free end disposed adjacent to the face of the door and also having an outwardly-extending loop-shaped portion adjacent to its middle, an arcuate, horizontally swinging arm pivoted to the door bracket and having a free end adjacent to the face of the door and also having an outwardly extending loop straddling and pivotally connected to the outwardly-extending loop-shaped portion of the first-named arm, and a retractile spring extending between and connected with the free ends of said arms.
2. In a door-closing device, the combination of a door frame, a door hinged thereto, an arcuate, horizontally swinging arm pivotally connected at one end with the face of the frame and having a free end disposed adjacent to the face of the door, an arcuate, horizontally swinging arm pivotally connected with the face of the door and pivot-

ally connected at an intermediate point of its length with the intermediate portion of the first-named arm and having a free end adjacent to the face of the door, and a retractile spring extending between and connected with the free ends of said arms and inclosed between the arms and the face of the door in approximate parallel relation to the latter.

3. A spring-actuated door closing device, comprising arms pivotally connected together adjacent to their middles, means at one end of one arm for attaching the same to a door frame, means at one end of the other arm for attaching same to a door, and a retractile spring extending between and connected with the opposite ends of the arms, whereby when the device is applied, the spring will be inclosed between the arms and the face of the door in approximate parallel relation to the latter.

In testimony whereof I affix my signature in presence of two witnesses.

ALBERT T. LOFTSGAARDEN.
